SHOE BUCKLE

Charles E. Weller, 77 Puritan Drive, Warwick, R.I.

Filed Apr. 19, 1962, Ser. No. 69,776

Term of patent 14 years

(Cl. D17—1)

FIG. 1

5
↓

FIG. 2

FIG. 3

FIG. 4

FIG. 5

FIGURE 1 is a perspective view of a shoe buckle, embodying my new design;

I claim:

The ornamental design for a shoe buckle, substantially as shown.
